CLAIM

The ornamental design for a mobile phone, as shown and described.

DESCRIPTION

FIG. 1 is a perspective view of a mobile phone showing my new design;

FIG. 2 is a front elevational view thereof;

FIG. 3 is a right side elevational view thereof;

FIG. 4 is a left side elevational view thereof;

FIG. 5 is a bottom plan view thereof;

FIG. 6 is a cross sectional view thereof taken along a line 6—6 of FIG. 2;

FIG. 7 is a cross sectional view thereof taken along a line 7—7 of FIG. 2;

FIG. 8 is an enlarged perspective view of the claimed portion of the mobile phone shown in FIGS. 1-7; and,

FIG. 9 is a cross sectional view of the mobile phone taken along lines 9—9 of FIG. 6.

The broken lines showing the remainder of the mobile phone are directed to environment and are for illustrative purposes only; the broken lines form no part of the claimed design.

1 Claim, 9 Drawing Sheets
